SECTIONAL ATHLETIC FIELD COVER

Cyrus J. Hoigaard and Frank W. Boeck, Minneapolis, Minn., assignors to C. J. Hoigaard Co., Minneapolis, Minn., a corporation of Minnesota

Application November 25, 1946, Serial No. 712,166

2 Claims. (Cl. 273—55)

1

This invention relates to sectional, flexible coverings for athletic fields and other large areas and particularly relates to a sectional covering having means provided for easily connecting and interlocking adjoining sections.

For some years flexible, waterproof coverings have been used to protect large areas such as athletic fields, airports, freshly laid concrete and the like.

The difficulty incurred in such coverings has been that either the flexible covering has been too large and cumbersome to be easily handled, or if in sections, there has been no quick way of interconnecting these sections to provide complete protection.

It is an object of our invention to provide a highly efficient, sectional covering of the class described, having readily connectible and disconnectible, cooperating sealing means between the several sections.

More specifically, it is an object to provide a continuous, sealing connection between adjacent sections of a flexible waterproof covering preventing water from running between the sections and securing the sections in a continuous, integral structure and eliminating interference from wind forces.

Another object is to provide, in a protective sectional covering, an underlying water-sealing fold, a sealing bead of unitary construction with interlacing loops to connect and continuously seal the underlying section to an adjacent overlapping edge of an adjoining section, thus providing a substantially continuous connection.

These and other objects and advantages of our invention will more fully appear from the following description made in connection with the accompanying drawings wherein like reference characters refer to the same or similar views and in which:

Fig. 1 is a fragmentary plan view showing the connected assembly of several sections of a flexible covering;

Fig. 2 is a top plan view showing the connected assembly of several sections of a flexible covering;

Fig. 2 is a top plan view showing the loops in interlaced position connecting two adjoining sections;

Fig. 3 is a top perspective view showing the interlacing method and the construction of the adjacent edges of two adjoining sections;

Fig. 4 is a detail section view taken substantially on the line 4—4 of Fig. 2, showing in elevation the loops in interlaced position;

Fig. 5 is a section view taken substantially on the line 5—5 of Fig. 1 showing the end view of the water-sealing connection; and

Fig. 6 is a vertical section taken similarly to Fig. 5 but showing an alternative method of

2

folding the top overlapping edge into the underlying water-sealing fold to provide additional sealing action.

All of the several sections of the flexible covering are similarly constructed. In the form shown, each section is made from an elongated, rectangular strip of waterproof canvas. Each of the sections at one of its marginal, longitudinal edges is stitched to form a relatively wide hem 7 and through said hem, a series of equally and longitudinally spaced apertures 9 are formed. A series of metal grommets 10 are inserted therethrough, being clinched against the fabric of the hem. The longitudinal edge of the hem is indicated by the numeral 8.

The opposite marginal and longitudinal edge of each section is stitched to form a hem 11 and a flexible, reinforcing element such as a rope 12 is firmly encased therein, forming a sealing bead 11a. Additional stitching may be utilized to secure the rope or element within the hem. The rope of said bead 11a also forms a series of equally spaced, interlacing loops 12a adapted to be inserted through the metal grommets 10. The length of the said loops 12a is substantially equal to the distance between two adjacent grommets 10.

The beaded marginal portion of each section is folded back, forming the underlying water-sealing fold 13, which fold is preferably stitched close to its line of folding.

A typical use for such a covering would be to protect a football gridiron. There the various sections would be laid out on the ground covering the playing field and arranged so that the grommets 10 of the hem 7 of one section respectively, overlie the loops 12a of the sealing bead 11a of the adjoining section. A typical connection is shown in Figs. 2 through 5, inclusive. In Fig. 3 the overlapping, grommet-containing hem 7 of a section designated A is shown in connecting position with the underlying marginal portion of the adjoining section designated B, which contains loops 12a and fold 13.

45 A hand loop 14 is provided at each end of the overlapping edge 8 of each section to facilitate aligning the holes with their respective loops and to receive a hold-down stake, thus preventing the wind from getting under the narrow ends 50 of the canvas sections.

The general procedure for making the connection is as follows. Adjoining sections are laid down with underlying loop-containing hem 11 of one section adjacent to the overlapping hem 7 of 55 the adjoining section. Then the loops 12a are successively inserted through their respective grommets 10. To this end, the loop second to the end is threaded through the end loop, the third loop being threaded through the second one, the 60 fourth through the third and so on across the

width of the entire covering (see Fig. 3). The last loop may be pulled out over the end of the canvas and staked down to the ground or it may be merely knotted on itself to hold the next to the last loop in interlaced position.

Since the length of each loop 12a is substantially equal to the distance between the grommets 10, such an interlacing process as described, will pull each loop 12a tightly down upon the overlapping hem 7 of section A, forcing the overlapping hem 7 down against the rope bead 12 and thereby forming a tight, continuous seal between adjoining marginal portions of section A and section B.

The reinforcing bead 11a causes each section to assume the shape of a slight trough, facilitating the drainage of water to the sides and away from the playing surface. Bead 11a further has a damming effect on any water which seeks to seep transversely between the connections. Combined with the sealing effect between the overlapping flap of section A and the said rope bead of section B, the underlying water-sealing flap 13 constitutes a dam to positively prevent the water from running laterally between the overlapped portions of adjacent sections.

The grommets 10 are so disposed inward from the edge 8 as to leave an overlying portion of the hem 7 shown in Fig. 5, merely resting on the overlying waterproof canvas, beyond sealing bead 11a.

Fig. 6 shows this flap or hem 7 tucked underneath the water-sealing bead 11a into the water-sealing fold 13, thus providing an alternative method of making connection between two sections. This alternative method shown in Fig. 6 provides additional protection and sealing action, the rest of the connection being substantially the same as outlined above.

In a typical use, such as a gridiron cover, the several sections may be of ten yards in width and of a length to traverse the entire playing field. The several sections are usually rolled up upon large tubular members such as culverts which facilitates laying and taking up of the covering as well as storage thereof.

In laying and interconnecting the sections of the protective covering, a crew of two or three operators is usually employed, one of the operators successively unrolling the sections with opposing longitudinal edges thereof, slightly overlapped. After the first section is laid, a second operator, as the second section is being unrolled, successively interlaces the loops 12a, first inserting a loop through the cooperating grommet of the overlapping section edge and then passing that loop through the bight of the preceding loop. In this manner, the sections may be interlocked and sealed as they are being unrolled and laid.

In taking up the covering, the operation is reversed and the loops are successively disengaged as the sections are being rolled.

Most playing fields, runways and the like are crowned transversely so that the moisture collected will run to the sides of the assembled structure.

From the foregoing description, it will be seen that we have provided a comparatively simple and highly efficient sectional protective covering adapted for wide general use and capable of being very quickly and easily assembled in operative position with the sections interlocked.

It will further be seen that the combination of the cooperating edges, folds and sealing beads of two adjacent sections provide a positive dam and trap between the joined marginal edges.

It will further be seen that a close combinative relation exists between the cooperating facilities for sealing and the particular means for locking and interlocking the sections in that the interlacing and tightening of the loops 12a provides a substantially continuous downward clamping effect against the overlapped marginal edge. This clamping effect forces the doubled or folded edge (in the form shown, the hem 7) against the top of the longitudinal bead 11a.

It will of course, be understood that various changes may be made in the form, details, arrangement and proportions of the parts without departing from the scope of our invention.

What we claim is:

1. A sectional protective covering for areas such as athletic fields having in combination, a plurality of elongated sections constructed of water repellent material each of said sections having one of its longitudinal edges overlapped against itself to form a water sealing fold with the free edge thereof unattached to the underlying marginal portion of the section and having a reinforcing water sealing bead connected along said unattached free edge of the water sealing fold, a series of longitudinally spaced interconnecting elements attached along said free edge, the opposite longitudinal marginal portion of each section having a plurality of spaced connecting elements for cooperating with said interconnecting elements to permit continuous sealing of the adjacent marginal portions of two adjoining sections.

2. A sectional protective covering for areas such as athletic fields having in combination a plurality of elongated marginally overlapping sections constructed of flexible water repellent material, each of said sections comprising a main body portion, a marginal fold formed along one longitudinal edge of said body portion being overlapping thereagainst with the free overlapped edge of said fold being unattached to said body portion to constitute a water confining trap under said fold, the other longitudinal edge portion having a plurality of section connecting elements disposed a short distance inwardly from the extreme edge thereof, and cooperating section connecting elements mounted adjacent the unattached free edge of said fold and cooperating with the first mentioned section connecting elements to interconnect adjacent edge portions of adjoining sections when adjoining sections are overlapped.
